US00D847901S

(12) United States Design Patent (10) Patent No.: US D847,901 S
(45) Date of Patent:  May 7, 2019

(54) LABEL

(71) Applicant: HYUNDAI MOBIS CO., LTD., Seoul (KR)

(72) Inventor: Eun Jung Kim, Yongin-si (KR)

(73) Assignee: HYUNDAI MOBIS CO., LTD., Seoul (KR)

() Term: 15 Years

(21) Appl. No.: 29/633,995

(22) Filed: Jan. 17, 2018

(30) Foreign Application Priority Data

Jan. 10, 2018 (KR) 30-2018-0001632

(51) LOC (11) Cl. 19-08

(52) U.S. Cl. ..... USPC D20/24; D20/25

(58) Field of Classification Search

USPC D20/10, 19, 21, 22, 25, 27, 28, 37, 40, D20/42, 43; D14/485-495

CPC G09F 1/00; G09F 1/02; G09F 1/04; G09F 1/06; G09F 1/08; G09F 9/00; G09F 13/00; G09F 2003/0264

See application file for complete search history.
